UNITED STATES PATENT OFFICE.

PAUL J. FREEMAN, OF EL RENO, OKLAHOMA.

ELECTRIC LANTERN.

Application filed June 20, 1928. Serial No. 286,903.

The present invention relates to improvements in electric lanterns and has reference more particularly to a lantern which is capable of vertical swinging movement with respect to its support, so that the light may be directed at any angle desired.

A further object is to provide an electric lantern of the above mentioned character, which includes an end lamp and a side lamp, 10 a single switch being provided for turning either of said lamps on or off when desired.

A still further object is to provide an electric lantern of the above mentioned character, wherein the supporting frame for the 15 flashlight has a bail pivotally associated with the upper end thereof to facilitate the carrying of the lantern, the frame further including a pair of opposed side bars between which the flashlight is pivotally adjusted for disposition at any angle.

A further object is to provide an electric lantern of the above mentioned character which is simple in construction, inexpensive, strong and durable, and further well adapted to the purpose for which it is designed.

Other objects of the invention will become apparent as the nature of the invention proceeds and when taken in connection with the accompanying drawings.

30 In the accompanying drawings, forming a part of this application and in which like numerals designate like parts throughout the several views:

Figure 1 is a side elevation of the electric 35 lantern embodying my invention, showing the flashlight secured in a vertical position with the bulb on the end of the flashlight facing downwardly.

Figure 2 is a similar view looking at right 40 angles to Figure 1.

Figure 3 is a vertical sectional view through the lantern.

Figure 4 is a transverse section taken approximately on the line 4-4 of Figure 3, 45 looking downwardly.

Figure 5 is a view similar to Figure 1, showing a modification of the frame construction.

Figure 6 is a view looking at right angles 50 to Figure 5, and

Figure 7 is a detail of the intermediate portions of the spaced arms constituting each side of the modified frame.

In the drawings, wherein for the purpose 60 of illustration is shown the preferred embodiment of my invention, the numeral 1

designates generally the frame of the electric lantern embodying my invention, the same including a ring like base 2, from which extends upwardly the opposed side 60 bars 3 and 5 respectively and the upper ends of these side bars have connection with the upper ring or band 5.

A bail 6 is pivotally associated at its ends with the ring 5, at diametrically opposite 65 points as at 7.

Threaded transversely through the intermediate portions of the side bars 3 and 4 are the thumb screws 8 and 9 respectively, the purpose thereof being hereinafter more 70 fully described.

The flashlight unit, which is designated generally by the unit 10 comprises a cylindrical casing 11, which is open at its respective ends, the hinged lid 12 being provided 75 for the upper end of this casing, and a spring clip 13 holds the lid in a closed position. The lower open end of the casing is externally threaded for receiving the lens holding ring 14, the lens which is in the 80 form of an enlarged bull's eye being shown at 15.

A conical reflector 16 is arranged in the lower end of the casing for disposition against the lens 15, and the smaller end of this reflector is formed with an inturned threaded neck 17 for receiving the threaded base of the electric lamp 18, as clearly shown in Figure 3 of the drawings.

A dry cell battery 19, of the conventional 90 construction is removably received within the casing 11 and a spring 20 is disposed between the lid 12 and the upper end of the battery for normally urging the same downwardly so that the terminal 21 of the battery 95 will be in engagement with the terminal of the electric lamp 18, as also shown very clearly in Figure 3.

The flashlight 10 is furthermore provided with a side lamp 22 that is arranged within an opening formed in the side of the casing 11 in the intermediate portion thereof and a lens 23 is supported over the electric lamp 22. A shade 24 is also arranged on the side of the casing directly above the lamp 22, as 105 clearly indicated in Figures 1 and 3 of the drawings.

A manually operable switch 30 is operable within a suitable guide 28 arranged for disposition over a slot formed in the side of the casing 11, for controlling the light of a side lamp 22. A similar switch 31 is arranged 110

for slidable movement within a suitable guide 32, also carried by the casing 11, for controlling the turning on and off of the lamp 13.

5 The lamps may be connected with the battery 19 along with the respective switches in any manner well known in the art as the same forms no part of the present invention a detailed description of the wiring is not 10 believed necessary.

The flashlight is arranged for pivotal movement within the frame 1 and to this end the casing is formed in its sides at diametrically opposite points with the trunnions 21 15 for receiving the pointed ends of the thumb screws 8 and 9. When the thumb screws are loosened the flash light 10 may be swung in any vertically adjusted position so that the ray of light from the lamp 18, when this 20 lamp is turned on may be projected in any desired direction and by tightening the thumb screws, the flash light units will be held in properly adjusted position.

Also by constructing the frame so that 25 the upper and lower ends are opened, the flashlight unit may be used to project the light rays either upwardly or downwardly through the frame.

One of the advantages of this feature is 30 that electrical lenses may be set on the ground beneath the street car while packing a hot box on a car or making any other repairs or adjustments which require the use of both hands; or under an automobile.

35 When checking a train, railroad men carrying their lantern on the left forearm have the bail around the upper portion of the arm. Here then is the advantage of the side light, in that it throws the light against the side 40 of the car, on the figures, etc., and on the train book carried by the workman which he holds in his left hand.

The shade will prevent the light from the side lamp shining into the trainmen's eyes.

45 In Figures 5 and 6 of the drawings, there is shown a modification of the frame construction, wherein the frame is formed entirely of wire, and is designated generally by the numeral 33. This frame comprises 50 a wire ring like base 34. The sides of the frame each consist of an elongated strand of wire, bent intermediate its ends to provide the spaced arms 35 and 36, respectively. The free ends of these arms are disposed 55 outwardly and are soldered to the ring-like base 34. The arm 35 is formed intermediate its ends with the coiled portion 37, and the adjacent portion of the arm 36 is welded to said coiled portion. The purpose of the 60 coiled portion 35 is to provide a means for receiving the threaded member 38 that is fixedly secured at its inner end to each side of the casing 11 of the flash light unit as at 39 and suitable thumb nuts 40 are threaded 65 on the outer end of each of these threaded

members 38. Manifestly, by turning the thumb nuts in one direction, the convolutions of the coiled portions 37 may be compressed, whereby to maintain the vertically swinging flashlight unit in any adjusted 70 position.

The upper end portion of each arm 35 is also formed with a coiled portion 41, through which extends a bolt 42, the bolt being adapted to extend also through an eye 75 43, formed at each end of the wire bail 44, and thumb nuts 45 are threaded on each bolt to properly secure the bail to the frame.

As is clearly illustrated in the drawings, with reference more particularly to Figures 80 5 and 6, the wire bail 44 is formed in each side adjacent the free end thereof with the finger gripping portions 46. This will permit the bail to be grasped at either side to facilitate handling of the latter.

85 Suitable reinforcing members 47 extend upwardly from the ring like base 34, at diametrically opposite points, and the upper ends of these reinforcing members are attached to the spaced arms 35 and 36 of 90 each side of the frame by a suitable clip 48. In this manner, the frame is rendered rigid.

The simplicity of my device enables the parts to be readily and easily assembled or disassembled and furthermore the flash 95 lights may be quickly adjusted for disposition at any desired angle within the frame.

While I have shown the preferred embodiment of my invention, it is to be understood that minor changes in the size, shape 100 and arrangement of parts may be resorted to, without departing from the spirit of the invention and the scope of the appended claims.

Having thus described my invention, what 105 I claim as new is:

1. In an electric lantern, a frame including a ring like base, a pair of vertically disposed opposed side members extending upwardly from the base, each of said side 110 members being formed from a single strand of wire bent intermediate its ends to provide a pair of spaced arms, the free ends of the arms being secured to the base, the intermediate portion of one arm being 115 formed with a coil, a carrying bail pivotally connected to the upper ends of the side members, a flash light unit arranged between the side members, pivot forming elements extending from diametrically opposite points of the flash light unit through the respective coils to provide a pivotal support for the flashlight unit, and means associated with the pivot forming members for cooperation with the respective coils to secure the flash light unit in any vertically adjusted position.

2. In an electric lantern, a frame including a ring like base, a pair of vertically disposed opposed side members extending up- 120 125 130

wardly from the base, each of said side members being formed from a single strand of wire bent intermediate the ends to provide a pair of spaced arms, the free ends of 5 the arms being secured to the base, the intermediate portion of one arm being formed with a coil, a carrying bail pivotally connected to the upper ends of the side members, a flash light unit arranged between the 10 side members, pivot forming elements extending from diametrically opposite points of the flash light unit through the respective coils to provide a pivotal support for

the flashlight unit, means associated with the pivot forming members for cooperation 15 with the respective coils to secure the flashlight unit in any vertically adjusted position, and reinforcing elements extending upwardly from the ring like base between the lower ends of the arms of each side member, 20 the upper ends of said reinforcing members being secured to the spaced arms of each side member.

In testimony whereof I affix my signature.

PAUL J. FREEMAN.
